United States Patent Office

Des. 190,669

Patented June 20, 1961

190,669

DINNER PLATE

Fred J. Krone, Chicago, Ill., assignor to P. R. Mallory & Co., Inc., Indianapolis, Ind., a corporation of Delaware

Filed Dec. 30, 1960, Ser. No. 63,404

Term of patent 14 years

(Cl. D44—15)

The figure is a plan view of a dinner plate of conventional configuration, showing my new design.

I claim:

The ornamental design for a dinner plate, as shown and described.
